UNITED STATES PATENT OFFICE.

THOMAS B. HOWE, OF SCRANTON, PENNSYLVANIA.

JOURNAL-LUBRICATOR.

SPECIFICATION forming part of Letters Patent No. 269,524, dated December 26, 1882.

Application filed October 14, 1882. (No model.)

To all whom it may concern:

Be it known that I, THOMAS B. HOWE, of Scranton, in the county of Lackawanna and State of Pennsylvania, have invented certain new and useful Improvements in Lubricators for Journals; and I do hereby declare the following to be a full, clear, and exact description of the same, reference being had to the accompanying drawings, forming part of this specification, in which—

Figure 1 is a perspective view of my improved lubricating device detached. Fig. 2 is a view showing the same arranged in a car-axle box for the lubrication of the journal of the car-axle. Fig. 3 is a view of a modified form of roller.

Similar letters of reference in the several figures denote the same parts.

My invention has for its object to provide an improved journal - lubricating device applicable to the journals of car-axles, shafting, and elsewhere generally, and which shall be adapted to supply a constant, uniform, and sufficient quantity of oil or other lubricating material to 25 the journal whenever the latter is revolved.

To this end my invention consists in the lubricator constructed and adapted for operation substantially as I will now proceed to describe, and point out in the claims at the end of this 30 specification.

In the drawings I have shown the application of my invention to the lubrication of the journal of a car-axle, though it is evident that it can be applied elsewhere with equal effect.

35 A represents the car-axle; B, the journal thereof; C, the car-axle box; D, the bearing for the journal, and E the slide above the bearing.

40 F represents the removable base-piece, constituting the main frame of the lubricator. Secured to or formed upon this base - piece are standards G G, on the upper portions of which are fulcrumed the arms h h of a bifurcated lever, H.

45 Suspended from the extremities of the arms h h of the lever by lugs or trunnions i i, located centrally of it, is a frame or carrier, I, preferably of quadrangular form, and journaled in this frame or carrier, so as to rotate freely therein, 50 is a roller, K, which may be covered with a suitable absorbent material—such, for instance,

as cotton waste or wicking—and having its axis parallel, or nearly so, with the axis of the car-axle.

The outer extremity of the lever H is weighted, 55 as shown at x, and operates to hold the roller K constantly against the journal B of the axle. The oil or other lubricating material is filled into the axle-box to about the height indicated by the dotted line M, so that the roller is partially submerged in it. When the journal revolves the roller, being in close contact with it, also revolves and transfers oil to the bearing in an even, constant, and efficient manner, as will be readily understood. The manner of 60 hanging the roller in the frame or carrier I, and the connection of the latter with the pivoted yielding lever H, forms a jointed connection, which permits the roller to at all times bear evenly upon the journal and to evenly 65 distribute the lubricating material thereon. The inner wall of the box is hollow, and contains a sliding cut-off, Z, which fits up against the axle and prevents the flow of oil along the same. Arms X, pivoted to standards Y, engage through slots W, with said slide, and their weighted outer ends, V, operate to hold said slide at all times close up to the shaft.

An elliptical roller may be employed—such as shown in Fig. 3—instead of the cylindrical 70 roller, if desired.

The lubricating attachment can be readily inserted in and removed from the car-axle box when desired.

Having thus described my invention, I claim 75 as new—

1. The combination of the removable base F, having standards G, the lever H, having arms h and weighted outer end, the frame or carrier I, having trunnions i i, and the roller 90 K, with the journal of the axle and the axle-box, for containing the lubricant, the whole arranged and adapted to operate substantially as described.

2. The combination, with the slotted walls 95 of the box, of the sliding cut - off Z and the weighted arms X, pivoted on the standards Y, substantially as described.

THOMAS B. HOWE.
